UNITED STATES PATENT OFFICE.

JAMES RYAN, OF GRAND RAPIDS, MICHIGAN.

SMOKE-CONSUMER.

No. 896,250.

Specification of Letters Patent. Patented Aug. 18, 1908.

Application filed July 17, 1907. Serial No. 384,279.

To all whom it may concern:

Be it known that I, JAMES RYAN, a citizen of the United States, residing at Grand Rapids, in the county of Kent and State of Michigan, have invented certain new and useful Improvements in Smoke-Consumers for Locomotives, of which the following is a specification.

My invention relates to improvements in forced draft appliances for locomotive boilers, and its objects are: first, to provide a means whereby a large portion of the smoke escaping from the burning coal may be returned to the fire box to be re-burned; and, second, to provide a means whereby a large amount of oxygen may be forced to the fire box to increase the combustion therein so that a large proportion of the smoke in the fire box will be consumed. I attain these objects by the mechanism illustrated in the accompanying drawing in which

Figure 1 is a longitudinal section of a locomotive boiler showing the draft circulation, and my appliance in position on the outside 25 of the boiler. Fig. 2 is a side elevation of a boiler cut away to show my appliance applied inside of the boiler, and Fig. 3 is a longitudinal section of the appliance showing a valve in the trumpet end of the pipe, and the 30 ingress of air back of the conjunction of the pipe that returns the smoke to the main conductor, and, also, showing a means for manipulating the valve in the trumpet end of the main conductor pipe.

Similar letters refer to similar parts throughout the several views.

1 represents the locomotive boiler. 2 represents the flues and 3 represents the fire box having any available form of grates, as 10, 40 for burning the necessary fuel for producing steam. It is a well known and generally accepted fact that from sixty to eighty per cent. of the heat generated in an ordinary fire box upon locomotives is carried off through the 45 smoke stack 12, and to obviate this great waste I have provided for capturing a portion of the carbon thrown off from the fuel in the fire box, in the form of smoke, &c., and returning it to the fire box thoroughly intermingled with oxygen by reason of a strong 50 inflow of air, induced by the rapid movement of the locomotive. The arrows 9 represent the passage of heat, smoke &c., from the fire box into and through the tubes 2, and the

arrows 9' represent the passage of said heat, 55 smoke &c., into the breeching and through the smoke stack 12. 8 represents the exhaust pipe through which the exhaust steam is forced from the engine cylinders. This pipe exhausts directly under the smoke stack 12 60 and induces a, so called, forced draft through the flues 2.

To make my device available I find it very advantageous to divide the opening at the back of the boiler and immediately under the smoke stack 12 by a partition 11 of any desired form, from a point at the end of the boiler above the flues 2 diagonally down to a point beyond the line of the exhaust pipe 8, but leaving a space below the lower end as a 70 flue for the passage of heat, smoke &c., as shown in Fig. 1. Having arranged this portion of the appliance I place a pipe 4 the length of the boiler, the front end of said pipe being made bell shaped, as at 5, so that it 75 will collect as much air as possible consistent with the capacity of the pipe; and the other end of the pipe is curved and made to pass into the fire box, as shown at 6, so that all air that is collected by the bell 5 will be forced 80 into the fire box, as indicated by the arrows 9". Thus far the only advantage gained is the greater amount of oxygen that is forced into the fire box to facilitate the combustion of the fuel, but I attain a further advantage 85 by placing a branch pipe, 7, down from the main pipe 4 and forming a bell thereon just below the partition 11, near the end of the boiler so that the flow of air through the pipe 4, as hereinbefore described, will siphon the 90 surplus smoke from the flues 2 into the pipe 4 and thence, with the current of air, through said pipe and into the fire box 3, where, being thoroughly mixed with the onrushing air, the surplus of oxygen that is mixed with the 95 smoke renders a heat sufficiently intense to cause nearly all of the carbon contained in the smoke to be consumed, thus not only increasing the combustion of fuel in the fire box, but providing, at small cost, an almost 100 perfect smoke consumer, and with no additional effort outside of the natural resistance of the atmosphere upon a rapidly moving train.

The pipe 4 may be placed outside of the 105 boiler, as shown in Fig. 1, or it may be passed through the boiler, as shown in Fig. 2, and I deem the latter position the best as the in-

flowing air is heated to such a degree that it will increase, rather than to retard, the efficiency of the fire.

In the above description I have simply set forth the appliance in its simple form. Its efficiency may be greatly increased by the use of proper valves properly manipulated, thus, in Fig. 3 I have shown a very desirable form of valve which consists of a funnel shaped lining 5' inside of the bell 5 of the pipe 4, having a long projecting end that is divided, as indicated by the line *a*, so that if the valve is held in the position indicated by its solid lines the opening at the end of the projecting pipe will be small and cut off the flow of air through it, while if the valve is projected out, as indicated by its dotted lines the opening into the pipe 4 will be larger and will allow a greater volume of air to pass, and with greater force. With this valve I have provided for holding it in normal position, indicated by the dotted lines, by means of a spring *c* acting upon a plunger *b*, which plunger is connected with the arm 5", which is integral with the valve so that any motion of the plunger will move the valve accordingly, and to actuate the valve against the spring I provide an actuating rod, as *d*, that is designed to pass back to the cab back of the fire box where it will be easily accessible to the engineer or fireman who can, thereby, manipulate the valve as he or they may desire. It is to be understood that I do not describe this as the only form of valve available for use upon this device, but simply as one of the many forms that may be applied for the purpose stated.

Another modification shown in Fig. 3 is the division of the main pipe into two channels, as 4 and 4', the channel 4' entering the pipe 4 some distance back of the entrance of the pipe 7 so that there can be no possible danger of the air that enters the bell 5 being forced back through the pipe 7 and thus prevent the free passage of hot air and smoke from the back end of the flues 2 to and through the pipe 4, as the connections shown in Fig. 3 insures a perfect siphoning of air through the pipe 7 into and through the pipe 4, as hereinbefore stated.

Having thus fully described my invention,

what I claim as new and desire to secure by Letters Patent of the United States, is:—

1. In combination with a locomotive boiler and its fire box, flues and smoke chamber, a partition extending from the boiler head above the flues diagonally out and down into the smoke chamber forming a draft flue in the chamber below the partition, an exhaust pipe opening into the smoke chamber above the partition, a pipe having a funnel shaped front end and extending back parallel with the boiler and curved to enter the fire box near the top of the boiler, and a curved branch pipe having a funnel shaped open end front of the flues below and parallel with the diagonal partition and leading into the parallel pipe back of the funnel shaped front end.

2. In combination with a locomotive boiler, a fire box, flues, and smoke chamber, a pipe longitudinal of the boiler and having its back end entering the fire box, a branch pipe leading from the smoke chamber into the main pipe and curved to form a continuous channel with the main pipe and having a funnel shaped end inclining downward and outward from the end of the boiler above the flues, an exhaust pipe opening into the smoke chamber above the funnel, an auxiliary pipe having a bell shaped funnel at the front end and opening into the main pipe, and valves in the auxiliary pipe for regulating the flow of air through the pipe.

3. In combination with a boiler, a fire box and a smoke chamber, a pipe longitudinal of the boiler with its back end entering the fire box, a branch pipe leading from the smoke chamber into the longitudinal pipe, a bell shaped funnel at the front end of this pipe, a bell shaped valve in said funnel, a plunger slidingly secured at one end to the main pipe and firmly secured at the other end to the valve, a spring on said plunger in position to actuate the valve in one direction, and a rod for actuating the valve in the other direction.

Signed at Grand Rapids Michigan July 15 1907.

JAMES RYAN.
